Primary Examiner — Kevin K Rudzinski*Assistant Examiner* — Woosuk K Shin(74) Attorney, Agent, or Firm — Stetina Garred Brucker & Newboles(57) CLAIM

The ornamental design for a lip balm dispenser as shown and described.

DESCRIPTION

FIG. 1 is an exploded top perspective view of the lip balm dispenser of the present invention showing my new design; FIG. 2 is a front view thereof;

FIG. 3 is a top view thereof; and,
FIG. 4 is a bottom view thereof.

The design shown in FIG. 2 is symmetrical about the longitudinal axis, and therefore, the rear, left-side, and right-side views are identical to the front view of FIG. 2. The portions of FIGS. 1 and 4 shown in broken lines do not form any part of the claimed design.
